WALLET WITH IMPROVED FOLDABLE PASS CASE

Simon Knee, Newark, N. J.

Application July 6, 1954, Serial No. 441,498

5 Claims. (Cl. 150—35)

My invention relates to wallets and more particularly to wallets provided with inserts of the type frequently referred to as pass cases.

One object of my invention is to provide a wallet insert which is adapted to be releasably secured in position in a wallet and which insert has a plurality of relatively foldable pockets or compartments arranged in such manner as to facilitate their manipulation for convenient observation of the contents thereof.

Another object of my invention is to provide a wallet insert which is adapted to be releasably connected to a wallet and which insert has a plurality of relatively foldable pockets and a money clip for holding money therein.

Another object of my invention is to provide a wallet insert which when releasably secured to a wallet provides means for holding paper money in such position that it will not be readily visible.

Yet another object of my invention is to provide a wallet insert which, if desired, may be employed separately from the wallet as an auxiliary lightweight wallet having relatively foldable pockets to carry photographs or cards and also means for holding paper money or other papers for convenient access and removal.

Other objects of my invention will become clear hereinafter as the characteristic features of construction and mode of use of my invention are described in detail.

In the accompanying drawings:

Fig. 1 is a plan view of an open wallet having a wallet insert embodying my invention releasably secured thereto;

Fig. 2 is a plan view of an open wallet having an insert embodying my invention which insert is open but its foldable pockets are in their folded or side-by-side condition;

Fig. 3 is a plan view of a wallet having an insert embodying my invention included therein, the insert having its relatively foldable pockets in open condition;

Fig. 4 is a plan view of a wallet having an insert embodying my invention, the foldable pockets of the insert being unfolded so as to place any money held by the money clip on the insert in condition to be seen;

Fig. 5 is a sectional view taken along the line 5—5 of Fig. 2;

Fig. 6 is a sectional view taken along the line 6—6 of Fig. 3;

Fig. 7 is a perspective view of a wallet insert embodying my invention; and

Fig. 8 is a sectional view taken along the line 8—8 of Fig. 7.

Referring to the drawings in detail, the reference numeral 10 designates a wallet which may be of any suitable design. As shown herein the wallet 10 has a rear or outer wall 12 and a front or inner wall 14 secured to the rear wall by any suitable means such as cement or a sewed seam or both. Between the front wall 14 and the rear wall 12 is a center partition 16 which is mounted for limited longitudinal sliding movement. Although not necessary to the invention, the center partition 16 and the rear wall 12 may have cooperating slide fastener members 18 for closing a paper money pocket defined by the two walls. An extension or flap 19 of rear wall 12 on the left side of the wallet, as viewed in Fig. 5, is folded over front wall 14 and secured to the latter by any suitable means so as to define a pocket 20. Of course, pocket 20 may be formed in other well known manner. For reasons which

2

will become clear hereinafter pocket 20 is provided with a slit 22 at the extreme left hand edge of pocket 20. As is well known in the design of wallets, there may also be provided on front wall 14 pockets 24 and 26 adapted to contain calling cards and stamps or other necessary items therein.

My invention resides in the wallet insert designated generally by the reference character 28. As best seen in Fig. 7, insert 28 is provided with a back wall 30 which is foldable along a transverse line 32 which substantially bisects the back wall. This wall may be made of any suitable pliable material and will usually be made of leather. A foldable wall 34 is secured to back wall 30 as viewed in Fig. 7 just to the left of transverse line 32 by two parallel spaced sewed seams 36 and 38. As best seen in Fig. 8, the seams 36 and 38 in cooperation with foldable wall 34 and back wall 30 define a slot 40. A hairpin shaped money clip 42 has one of its legs inserted into slot 40 through an aperture 44 in foldable wall 34, the other leg being outside the slot and biased toward engagement with wall 34, for holding the money clip in the described position.

Foldable wall 34 is provided with two square apertures 46 and 48 disposed so as not to be intersected by the line 49 along which wall 34 may be folded. Secured to wall 34 by suitable means, such as sewed seams or cement or both, are two apertured wall members 50 and 52 which preferably have their apertures in alignment with the apertures 46 and 48 in foldable wall 34. A relatively pliable transparent material such as Celluloid may be placed over the apertures so as to enclose them to form relatively foldable pockets which are viewable from either side.

Secured to the right hand wall portion of back wall 30 is another apertured wall member 54 which cooperates with the back wall to form another pocket thereon. The aperture in member 54 will also be enclosed by a transparent pliable material. It will be seen that when foldable wall 34 is in its folded position, as best shown in Figs. 2 and 5, the first or left hand portion of the back wall will be obscured from view by the pockets being folded in side-by-side relation with the left hand portion of the back wall so that if any paper money is secured to the money clip 42, it will not be visible. This advantage is maintained whether the insert is used in a wallet or by itself.

At the extreme left hand end of the left hand portion of back wall 30 is a tab 56 which has secured thereto a female snap member 58, and secured to the rear of the right hand portion of back wall 30 is a male snap member 60 which cooperates with female member 58 to hold the wallet insert in its folded condition in or out of wallet 10. It will be obvious that other types of securing means may be used in place of snap members 58 and 60.

The left hand portion of back wall 30 is adapted to be inserted into pocket 20 of wallet 10 with tab 56 extending through slit 22 as may best be seen in Figs. 2, 4 and 5. With the left hand portion of wall 30 so inserted, it will be obvious that wallet insert 28 will remain in the described disposition so that the owner of the wallet may display any cards or photographs held in the pockets. It will also be obvious that with the pocket arrangement described heretofore, the owner of the wallet will have a substantially large number of pockets which may be so folded as to reduce the bulk of the insert and hence the bulk of the wallet. In addition, with the wallet insert disposed in pocket 20 and pockets defined by apertured wall members 50, 52 and 54 being simultaneously viewable, as shown in Fig. 3, the length of the entire assembly is not unduly increased since the pockets defined by apertured wall members 52 and 54 both overlie the wallet. Furthermore, when the insert is positioned in pocket 20,

any paper money being held by the money clip 42 may also be inserted in pocket 20 so as to obscure the money from view even in the event that the foldable pockets are folded to the position best shown in Fig. 4, that is with flap 19 of wall 12 clearly visible. Accordingly, unless the wallet owner intentionally moves the wallet insert to the right as shown in Fig. 4, any money contained in pocket 20 and held there by money clip 42 will not be visible.

Another advantage of my novel wallet insert is that it may be removed from wallet 10 so as to serve as a compact wallet in and of itself. Although the wallet insert cannot fulfill all the desired functions of an ordinary wallet such as wallet 10, it has provision for carrying cards and photographs and the like and also for carrying paper money and it has the advantage of having very little bulk so that it will be ideally suited for use with evening wear or the like. When used as an auxiliary wallet by itself, wallet insert 28 may be held in a closed condition with the foldable pockets in side-by-side relation by the snap members 58 and 60 to thereby assure that the wallet insert will be of minimum bulk.

Although I have herein shown and described only one form of wallet insert embodying my invention, it will be clear that various changes and modifications may be made therein within the scope of the appended claims without departing from the spirit and scope of my invention.

Having thus described my invention, what I claim and desire to secure by Letters Patent is:

1. A wallet insert for use with a wallet or separately therefrom, said insert comprising a back wall foldable along a transverse line to form two substantially congruent cover portions, said one back wall portion being adapted to be inserted into a pocket of a wallet, a foldable apertured wall secured at one end to said back wall adjacent said transverse line, a plurality of apertured wall members secured to said apertured wall with the apertures of said plurality of wall members being in substantial registry with the apertures of said apertured wall to form a plurality of apertured pockets foldable from a superposed side-by-side condition in which they overlie one or the other of said portions of said back wall to a condition in which they are in an end-to-end relation and overlie one or the other of said back wall portions, another apertured wall member secured to the other back wall portion to form another pocket which when said back wall is unfolded will be either in end-to-end relation or side-by-side relation with said relatively foldable pockets depending upon the condition of said relatively foldable pockets.

2. A wallet insert for use with a wallet or separately therefrom, said insert comprising a back wall foldable along a transverse line to form two substantially congruent cover portions, said one back wall portion being adapted to be inserted into a pocket of a wallet, a foldable apertured wall secured at one end to said back wall adjacent said transverse line, a plurality of apertured wall members secured to said apertured wall with the apertures of said plurality of wall members being in substantial registry with the apertures of said apertured wall to form a plurality of apertured pockets foldable from a superposed side-by-side condition in which they overlie one or the other of said portions of said back wall to a condition in which they are in an end-to-end relation and overlie one or the other of said back wall portions, a money clip secured to said one back wall portion between its end edge and said transverse line so that when at least one of said foldable pockets overlies said one back wall portion, any money being held by said money clip will be concealed from view.

3. A wallet insert for use with a wallet or separately therefrom, said insert comprising a back wall foldable along a transverse line to form two substantially congruent cover portions, one of said portions having a tab

on its end remote from said transverse line, said one back wall portion and said tab being adapted to be inserted into a slotted pocket of a wallet so that said tab will extend through said slit, a foldable apertured wall secured at one end to said back wall adjacent said transverse line, a plurality of apertured wall members secured to said apertured wall with the apertures of said plurality of wall members being in substantial registry with the apertures of said apertured wall to form a plurality of apertured pockets foldable from a superposed side-by-side condition in which they overlie one or the other of said portions of said back wall to a condition in which they are in an end-to-end relation and overlie one or the other of said back wall portions, another apertured wall member secured to the other back wall portion to form another pocket which when said back wall is unfolded will be either in end-to-end relation or side-by-side relation with said relatively foldable pockets depending upon the condition of said relatively foldable pockets, a money clip secured to said one back wall portion between its end edge and said transverse line so that when at least one of said foldable pockets overlies said one back wall portion, any money being held by said money clip will be concealed from view, and means associated with said tab and said other back wall portion for holding the entire insert in a folded condition.

4. A wallet insert for use with a wallet or separately therefrom, said insert comprising a wall foldable along a transverse line to form two wall portions, a wall member secured to one of said wall portions along marginal edge portions thereof to form a pocket, a foldable wall secured at one end to said first mentioned wall adjacent said transverse line, wall members secured to said foldable wall along marginal edge portions thereof to form a plurality of pockets, means defining an access opening to each of said pockets, said plurality of pockets being foldable from a superposed side-by-side condition in which they overlie one or the other of said two wall portions to a condition in which they are in an end-to-end relation and overlie one or the other of said two wall portions, said first mentioned pocket in the unfolded condition of said first mentioned wall being either in end-to-end relation or side-by-side relation with said plurality of pockets depending upon the condition of the latter.

5. A wallet insert for use with a wallet or separately therefrom, said insert comprising a wall foldable along a transverse line to form two wall portions, a wall member secured to one of said wall portions along marginal edge portions thereof to form a pocket, a foldable wall secured at one end to said first mentioned wall adjacent said transverse line, wall members secured to said foldable wall along marginal edge portions thereof to form a plurality of pockets, means defining an access opening to each of said pockets, said plurality of pockets being foldable from a superposed side-by-side condition in which they overlie one or the other of said two wall portions to a condition in which they are in an end-to-end relation and overlie one or the other of said two wall portions, said first mentioned pocket in the unfolded condition of said first mentioned wall being either in end-to-end relation or side-by-side relation with said plurality of pockets depending upon the condition of the latter, and a money clip secured to the other of said wall portions adjacent said transverse line so as to underlie said plurality of pockets in said superposed side-by-side condition thereof in which they overlie said other wall portion.
